CHARLES C. TOMKINSON, OF PLAINFIELD, NEW JERSEY, ASSIGNOR TO J. EDWARD OGDEN, OF MOUNTAINVILLE, NEW YORK.

DOOR-COUNTERBALANCING SYSTEM.

1,253,302.

Specification of Letters Patent. Patented Jan. 15, 1918.

Application filed October 10, 1916. Serial No. 124,806.

To all whom it may concern:

Be it known that I, CHARLES C. TOMKINSON, a citizen of the United States of America, and a resident of Plainfield, Union 5 county, and State of New Jersey, have invented certain new and useful Improvements in Door-Counterbalancing Systems, of which the following is a specification, reference being had to the accompanying 10 drawings, forming a part thereof.

My invention relates to improvements in systems of counterbalancing that type of doors which move vertically and away from the vertical in opening, and its object is to 15 provide a simple arrangement of one or more auxiliary weights on the door or doors to act in conjunction with a main counterweight in such a manner as to produce a uniform balance for the doors in the various 20 positions they assume during their operation.

In order that my invention may be thoroughly understood, I will now proceed to describe the same in the following specification, 25 and then point out the novel features thereof in appended claims.

Referring to the drawings:

Figure 1 is a sectional side elevation of a 30 two-section door of well known construction with my invention applied thereto, the door being shown in three of the positions it assumes during its operation.

Fig. 2 is a front elevation of a part of one 35 of the door sections illustrating a detail of construction,—a simple arrangement for affixing one of the auxiliary weights.

Fig. 3 shows a modified structure in side 40 elevation in which head chains are used instead of shelf brackets to raise or support the inner ends of the door sections in their open position.

Corresponding parts are designated by the same reference characters in all the figures.

45 10 designates one of the side posts of a door opening, 11 its threshold, and 12 its lintel.

20 is a lower door section, on the lower 50 corners of which are rollers 21 which run on vertical tracks 22 throughout the entire length of the door opening. Hoisting chains 23 are affixed to the lower corners of this lower door section and extend up to sheaves 24 affixed to a transverse shaft 25 and down

to the main counterweight 26. 27 designates 55 the mechanism for rotating shaft 25 and 28 a hand chain for actuating this mechanism.

30 is an upper door section provided at its vertical edges with guides 31 into which the lower door section slides. Links 32 are pivoted at 33 to the edges of this upper door section near the center thereof and the other ends of the links are pivoted at 34 to fixed points above the door opening.

When such a door is operated the first 65 movement will be the vertical rise of the lower door section into the guides 31 until its lower edge is about even with the lower edge of the upper door section. This part 70 of the door movement is represented by the line A in Fig. 1.

A further upward movement of the lower edge of the lower door section will carry the lower edge of the upper door section with it, but the other parts of both door sections will 75 swing inwardly being supported by the hoisting chains 23 and the links 32. The door sections will assume the positions indicated by broken lines and designated 20^a, 30^a, and this part of their movement is represented by the line B.

At this part of the travel of the door sections a roller 29 supported on the back of the lower door section near the top thereof, will reach the position 29^a where it is about 85 to run upon a stationary shelf bracket 35.

During the rest of the opening door movement, that represented by the line C, the inner end of the door sections will be supported by the shelf bracket. When the door is 90 fully opened its sections will be in the position in which they are indicated by broken lines and designated by 20^b—30^b, and the roller will be in the position 29^b. Instead of the shelf bracket 35, head chains 50 (Fig. 95 3) sometimes are used to support the weight of the inner edges of the door sections when opened.

When the two door sections are of such construction that their weight is uniformly 100 distributed and are of about the same size, shape and weight, a uniform balancing effect is required throughout the whole travel of the door and the counterweight 26 will give the desired uniform balancing effect. 105 This is because of the fact that while the lower door section is rising alone its center of gravity rises therewith uniformly at the

ceive its charge by slackening the draft-rope 24. The charge is then lifted by drawing the rope 24, the pawl 15 gripping the pipe 8 prevents the detent member from sliding upon the pipe and prevents the traveling pulley from moving upon the pipe 9 so that the charge taken up by the fork will be lifted by the hoist to an elevation above the top of the wagon that is to receive the load. When a sufficient elevation has been reached by the hoisting apparatus, the handle 21 of the detent member is manipulated so that the pawl 15 is swung laterally out of contact with the traveling pulley 13 thereby allowing the latter to run upon the pipe 9 and convey the hoist and fork with its load to a position over the wagon where the load may be released in the customary manner by manipulating the trip cord 30. The hoisting apparatus is then returned to its former position for receiving a new charge. As the manure is removed from the ground by the fork either one or the other of the sleds may be drawn so that the fork will be brought from place to place as the available quantity of manure becomes exhausted.

What I claim is:

1. In apparatus of the class described, two parallel pipes spaced apart and in horizontal position; means for supporting said pipes at their respective ends in fixed relation with each other; a traveler supported by the lowermost of said pipes; a movable detent member on the uppermost of said pipes, and a pawl pivoted in the detent member having a

shoulder for engaging the pipe upon which the detent member is mounted when the traveler bears against the pendent end of the pawl in one direction.

2. In apparatus of the class described, two parallel supporting pipes; a traveler on one of the pipes; a detent device movably mounted upon the other of said pipes and adapted to engage and detain the traveler from passing in one direction; and a handle for turning the detent member upon its support out of engagement with the traveler.

3. In combination with a pair of parallel tracks, horizontally disposed, a traveler mounted upon one of the tracks; and a detent member adjustably mounted upon the other of said pipes adapted to engage the traveler and stop its movement in one direction.

4. In combination with a supporting track; a weighted collar slidably mounted upon the track and adapted also to be turned laterally thereupon; a handle attached to the collar for manipulating the same; and a pawl pivoted in connection with the collar and having a shoulder adapted to bear against the track and bind the collar in fixed position upon the track when the pawl is pressed in one direction.

In testimony whereof I affix my signature, in presence of two witnesses.

FRANK C. TOBIAS.

into direct opposition to the counterweight 26 during these door movements B and C and will restore the balance.

In the same arrangement shown in Fig. 5 3, a head chain 50 attached to the upper end of the upper door section at 51 and to a fixed point 52, is used instead of a shelf bracket to support or to raise the inner ends of the door sections when open. The function of 10 the auxiliary weights is similar in this case to that previously described.

In some cases it is feasible to determine the amount and positions of the weights 40 and 43 during the manufacture of the doors.

15 In such cases the auxiliary weights may be built into the door structure if desired. In other cases the conditions attending the erection of the doors change the weights of the door sections so that for nicety of balancing effects, the final positions of the auxiliary weights have to be determined or adjusted after the installation is complete.

20 I have illustrated my invention as applied to one type of door, but it is not limited to 25 a door of any particular design or construction, and in fact I intend no limitation other than those imposed by the following claims.

What I claim is:

1. A door having a vertically moving portion, and another part arranged to move away from the plane of said movement, a counterweight connected with said vertically moving portion of the door, and an auxiliary weight affixed to said other part of the door 35 in such a position as to have a variable counteracting effect upon the counterweight to maintain the balance of the door in its different positions.

2. A door having means for guiding its lower edge in a vertical plane, and means 40 for swinging the rest of the door away from said vertical plane, a counterweight connected with the lower edge of said door, and an auxiliary weight affixed to another part 45 of the door in such a position as to have a variable counteracting effect upon the counterweight to maintain the balance of the door in its different positions.

3. A door having means for guiding its lower edge in a vertical plane, means for 50 swinging the rest of the door away from said vertical plane, a counterweight connected with the lower edge of said door, an auxiliary weight affixed to another part of 55 the door in such a position as to have a variable counteracting effect upon the counterweight, and means for permitting the adjustment of the position of said auxiliary weight on the door to thereby change its 60 variable effect upon the counterweight.

4. A door having means for guiding its lower edge in a vertical plane, and means for swinging the rest of the door away from 65 said vertical plane, and means for supporting the weight of the part of the door which

moves away from the vertical plane as the lower edge of the door approaches the upper end of its path of travel, a counterweight connected with the lower edge of said door, and an auxiliary weight on the door above 70 its lower edge.

5. A door structure comprising a plurality of sections, the lower edges of which move in a vertical plane, and means for swinging said door sections away from said vertical 75 plane during a part of the door opening movement, a counterweight connected with the vertically moving part of the door structure, and auxiliary weights affixed to the door sections in such positions as to have 80 a variable counteracting effect upon the counterweight to maintain the balance of the door in its different positions.

6. A door structure comprising a plurality of sections, the lower edges of which move 85 in a vertical plane and means for swinging said door sections away from said vertical plane during a part of the door opening movement, a counterweight connected with the vertically moving part of the door structure, auxiliary weights on the door sections 90 in such positions as to have a variable counteracting effect upon the counterweight, and means for permitting the adjustment of the positions of said auxiliary weights on 95 the door sections to thereby change their variable effect upon the counterweight.

7. A door structure comprising a plurality of sections, the lower edges of which move in a vertical plane and means for swinging 100 said door sections away from said vertical plane during a part of the door opening movement, and means for supporting the parts of the door sections which move away from the vertical plane as the lower edges 105 of the door sections approach the upper end of their path of travel, a counterweight connected with the vertically moving part of the door structure, and auxiliary weights affixed to the door sections in such positions 110 as to have a variable counteracting effect upon the counterweight to maintain the balance of the door in its different positions.

8. A door structure comprising a plurality of sections, the lower edges of which move 115 in a vertical plane and means for swinging said door sections away from said vertical plane during a part of the door opening movement, and means for supporting the parts of the door sections which move away 120 from the vertical plane as the lower edges of the door sections approach the upper end of their path of travel, a counterweight connected with the vertically moving part of the door structure, auxiliary weights on the 125 door sections in such positions as to have a variable counteracting effect upon the counterweight, and means for permitting the adjustment of the positions of said auxiliary weights on the door sections to thereby 130

change their variable effect upon the counterweight.

9. A door structure comprising a plurality of sections, the lower edges of which move in a vertical plane, and means for swinging said door sections away from said vertical plane during a part of the door opening movement, a counterweight connected with the vertically moving part of the door structure, and an auxiliary weight affixed to one of the door sections in such position as to have a variable counteracting effect upon the counterweight.

10. A door structure comprising a plurality of sections, the lower edges of which move in a vertical plane and means for swinging said door sections away from said vertical plane during a part of the door opening movement, a counterweight connected with the vertically moving part of the door structure, an auxiliary weight on one of the door sections in such position as to have a variable counteracting effect upon the counterweight, and means for permitting the adjustment of the position of said auxiliary weight on the door section to thereby change its variable effect upon the counterweight.

11. A door structure comprising a plurality of sections, the lower edges of which move in a vertical plane and means for swinging said door sections away from said vertical plane during a part of the door opening movement, and means for support-

ing the parts of the door sections which move away from the vertical plane as the lower edges of the door sections approach the upper end of their path of travel, a counterweight connected with the vertically moving part of the door structure, and an auxiliary weight affixed to one of the door sections in such position as to have a variable counteracting effect upon the counterweight.

12. A door structure comprising a plurality of sections, the lower edges of which move in a vertical plane and means for swinging said door sections away from said vertical plane during a part of the door opening movement, and means for supporting the parts of the door sections which move away from the vertical plane as the lower edges of the door sections approach the upper end of their path of travel, a counterweight connected with the vertically moving part of the door structure, an auxiliary weight on one of the door sections in such position as to have a variable counteracting effect upon the counterweight, and means for permitting the adjustment of the position of said auxiliary weight, on the door section, to thereby change its variable effect upon the counterweight.

In witness whereof, I have hereunto set my hand this 28th day of September, 1916.

CHARLES C. TOMKINSON.
